UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

LEVER SWITCH FOR ELECTRIC SOCKETS.

Application filed June 28, 1922. Serial No. 571,393.

To all whom it may concern:

Be it known that I, REUBEN B. BENJAMIN, a citizen of the United States, residing at Chicago, in the county of Cook and State 5 of Illinois, have invented new and useful Improvements in Lever Switches for Electric Sockets, of which the following is a full, clear, concise, and exact description, reference being had to the accompanying 10 drawing, forming a part of this specification.

My invention relates to lever switches and more particularly to lever switches arranged for use in electric light sockets.

One of the objects of my invention is to provide an improved lever switch which will be of comparatively small size and capable of breaking comparatively heavy current and one which may be easily confined within 20 in the limits of the base of an ordinary electric lamp socket.

Another object of my invention is to provide a lever switch which will be durable and efficient in use, simple in construction, 25 of few parts and cheap to manufacture.

A further object of my invention is to improve certain features of switch construction.

Further objects will appear from the detailed description to follow and from the appended claims.

In the drawings in which an embodiment 35 of my invention is shown;

Figure 1 is a vertical longitudinal section showing my improved switch as used in an ordinary lamp socket, the operating lever being shown in full lines;

Fig. 2 is a bottom plan view of the socket interior and switch as shown in Fig. 1;

Fig. 3 is a top plan view of the socket interior;

Fig. 4 is a top plan view of the lower base of the socket interior showing the switch mounted thereon;

Fig. 5 is a transverse section taken on line 5-5 of Fig. 4;

Fig. 6 is a transverse section taken on line 6-6 of Fig. 4;

Fig. 7 is a section through the socket interior and the switch and taken on line 7-7 of Fig. 4;

Fig. 8 is a transverse section taken on line 8-8 of Fig. 4;

Fig. 9 is a perspective view of one of the contacting members; and

Fig. 10 is a sectional view of the switch showing the parts in the on-position, the off-position being shown by dotted lines.

Referring now to the drawings in detail, in my invention as illustrated, I provide a lower insulating switch base 10 on which are mounted a threaded shell contact 11 and a center contact 12, and an upper insulating base 13 on which are located the binding terminals 14 and 15, the socket interior 65 thus formed being enclosed in an ordinary casing 16.

The switch illustrated is mounted between the bases 10 and 13 and comprises a U-shaped member 17 having a pair of switch 70 blades or arms 18, a slide portion 19, and a coil compression spring 20 which holds the slide portion 19 against the inner end of the switch lever 21 as shown in Figs. 1, 7 and 10.

The switch lever 21 is provided with a cam member comprising two oppositely inclined portions 22 and 23 meeting at a crest 24.

When the handle 25 of the switch lever 80 21 is pushed upwardly in the position shown by dotted lines in Fig. 10, the U-shaped member 17 is pushed outwardly against the tension of the compression spring 20 until the crest 24 of the cam member passes 85 the point of application of pressure of the spring 20; the slide 19 is given a quick oscillation from a position from which it is in engagement with one of the inclined portions, as shown in full lines in Fig. 10, 90 to the position in which it is in engagement with the other inclined portion, as shown by dotted lines in Fig. 10; this quick oscillation of the slide 19 causes also a quick oscillation of the switch arms 18 to make 95 or break the circuit.

The spring 20 is located between the switch arms 18 and in a recess 26 between the insulating bases 10 and 13 and is provided with a transversely extending bearing member 27 which is seated in the bearing notches 28 in the U-shaped member 17. This transversely extending portion 27 also serves to guide the end of the spring as it extends into oppositely disposed guide slots 100 29 and 30 between the bases 10 and 13 as 105

shown in Fig. 4, the opposite end of the spring bearing against the insulating bases as shown in Fig. 1.

The U-shaped contact member 17 controls the circuit between the wiring terminals, and for this purpose a pair of contact members 31 and 32 are provided, the contact member 32 being electrically connected with the center contact 12 by means of the eyelet 33, and the contact 31 being electrically connected with the wiring terminal 14 by means of the screw 34 as shown in Fig. 5. The shell contact 11 is electrically connected to the wiring terminal 15 by means of the screw 35 as illustrated in Fig. 5.

When the contact blades 8 of the switch snap down into engagement with the contacts 31 and 32, the circuit is completed between these contacts, as the switch blades 18 are formed as a part of the U-shaped sheet metal stamping 17; when the contact blades 18 snap out from between these contacts 31 and 32 the circuit is broken.

The handle 25 of the switch lever 21 extends through an opening 36 in the casing 16 and is arranged to be operated by means of the thumb or finger to produce a quick make or break action of the switch.

The switch lever 21 is supported on the bearing 37 which extends into the notches 38 in the insulating bases 10 and 13.

While I have shown but one form of my invention it is obvious that it may be embodied in other forms as covered and defined by the appended claims.

Having thus described my invention, what I claim as new and desire to secure by Letters Patent is:

1. A lever switch comprising a pivoted operating lever, a pivotally and slidably mounted switch arm, the pivot of which is slideable toward and from the pivot of the operating lever, spring means for forcing the pivot of the switch arm toward the pivot of the operating lever, said switch arm carrying a bearing member having a bearing surface extending transversely of the line of spring pressure, said pivoted operating lever having a bearing point movable along said surface past the dead center between said pivots, to cause a snap action of the switch arm when said point passes the said dead center.

2. A lever switch comprising a pivoted operating lever, a pivotally and slidably mounted switch arm, the pivot of which is slideable toward and from the pivot of the operating lever, spring means for forcing the pivot of the switch arm toward the pivot of the operating lever, said switch arm carrying a bearing member having a bearing surface extending transversely of the line of spring pressure, said pivoted operating lever having a bearing point movable along said surface past the dead center between

said pivots, to cause a snap action of the switch arm when said point passes the said dead center, said operating lever having a stop portion engaged by said bearing surface to limit the snap movement.

3. A switch comprising a pivoted operating member, a pivotally and slidably mounted switch arm, the pivot of which is slideable toward and from the pivot of the operating member, spring means for pressing the pivot of said switch arm toward the pivot of said operating member, said switch arm carrying a bearing member having a bearing surface extending transversely of the line of spring pressure, said pivoted operating member having a bearing point movable along said surface past the dead center between said pivots to cause a snap action of the switch arm, and a two-part insulating base between the parts of which said switch mechanism is housed.

4. A switch comprising a pivoted operating member, a pivotally and slidably mounted switch arm, the pivot of which is slideable toward and from the pivot of the operating member, spring means for pressing the pivot of said switch arm toward the pivot of said operating member, said switch arm carrying a bearing member having a bearing surface extending transversely of the line of spring pressure, said pivoted operating member having a bearing point movable along said surface past the dead center between said pivots to cause a snap action of the switch arm, an insulating base on which said switch mechanism is mounted, having a recess therein, said spring means comprising a coil compression spring mounted and guided for movement in said recess.

5. A switch comprising a pivoted operating member, a pivotally and slidably mounted switch arm, the pivot of which is slideable toward and from the pivot of the operating member, spring means for pressing the pivot of said switch arm toward the pivot of said operating member, said switch arm carrying a bearing member having a bearing surface extending transversely of the line of spring pressure, said pivoted operating member having a bearing point movable along said surface past the dead center between said pivots to cause a snap action of the switch arm, and a two-part insulating base between the parts of which said switch mechanism is housed, the pivot of said switch arm being slideable between and guided for movement by and between the parts of said insulating base.

6. A lever switch comprising a pivoted operating lever, a pivotally and slidably mounted switch arm, the pivot of which is slideable toward and from the pivot of the operating lever, spring means for forcing the pivot of the switch arm toward the pivot of the operating lever, said switch arm car-

rying a bearing member having a bearing surface extending transversely of the line of spring pressure, said pivoted operating lever having a bearing point movable along said 5 surface past the dead center between said pivots, to cause a snap action of the switch arm when said point passes the said dead center, said spring means and the pivot of said switch arm being formed as parts of an 10 integral wire bent to provide a coil compression spring and a transversely extending slidable pivot pin.

7. A lever switch comprising a pivoted operating lever, a pivotally and slidably 15 mounted switch arm, the pivot of which is slidable toward and from the pivot of the operating lever, spring means for forcing the pivot of the switch arm toward the pivot of the operating lever, said switch arm carrying a bearing member having a bearing surface extending transversely of the line of 20 spring pressure, said pivoted operating lever having a bearing point movable along said surface past the dead center between said 25 pivots, to cause a snap action of the switch arm when said point passes the said dead center, said switch arm comprising a U-shaped member, the arms of which form contact members and the cross-bar of which 30 forms the bearing member.

8. A lever switch comprising a pivoted operating lever, a pivotally and slidably mounted switch arm, the pivot of which is 35 slidable toward and from the pivot of the operating lever, spring means for forcing the pivot of the switch arm toward the pivot of the operating lever, said switch arm car-

rying a bearing member having a bearing surface extending transversely of the line of spring pressure, said pivoted operating 40 lever having a bearing point movable along said surface past the dead center between said pivots, to cause a snap action of the switch arm when said point passes the said dead center, said spring means comprising 45 a coil compression spring and said switch arm comprising a U-shaped member, the arms of which form contacts straddling the coil compression spring.

9. A lever switch comprising a pivoted operating lever, a pivotally and slidably mounted switch arm, the pivot of which is slidable toward and from the pivot of the operating lever, spring means for forcing the pivot of the switch arm toward the pivot 50 of the operating lever, said switch arm carrying a bearing member having a bearing surface extending transversely of the line of spring pressure, said pivoted operating 55 lever having a bearing point movable along said surface past the dead center between said pivots, to cause a snap action of the switch arm when said point passes the said dead center, said spring means comprising a coil compression spring, and said switch arm comprising a U-shaped member, the arms of 60 which form contacts straddling the coil compression spring and have openings therein to receive the slidable pivot member of the 65 switch arm.

In witness whereof, I have hereunto subscribed my name,

REUBEN B. BENJAMIN.
